BOILER CLEANER

Henry T. Weis, New York, N. Y., assignor to Diamond Power Specialty Corporation, Detroit, Mich., a corporation of Michigan

Application April 24, 1933, Serial No. 667,573
Renewed January 24, 1936

14 Claims. (Cl. 122—392)

The invention is directed to an improvement in boiler cleaners, particularly of the type wherein a nozzled element is located within the boiler setting and is provided with nozzles for the discharge of cleaning fluid adjacent the parts of the boiler to be cleaned.

In particular, the invention resides in the provision of fluid cooled means to protect the cleaner element from the heat of the combustion chamber, and to provide fluid cooled means for the support of the cleaner element.

In one of its aspects, the invention is an improvement over my prior Patent 1,849,737, issued March 15, 1932.

Other features and advantages of the invention will be apparent as the description proceeds, reference being had to the drawings, wherein:

Figure 1 is a view, partly in elevation and partly in section, showing the invention applied to a boiler of the water tube type;

Figure 2 is a fragmentary detail, taken as regards the element, bearings, and boiler tubes, substantially on line 2—2 of Figure 1;

Figure 3 is an enlarged section on line 3—3 of Figure 1;

Figure 4 is a diagrammatic view of the piping connections;

Figure 5 is a longitudinal section through the operating head; and

Figure 6 is a longitudinal section, partly in elevation and broken away, of a modification.

In Figure 1 is indicated the application of one form of the invention to a boiler of the conventional water tube type. In this figure is shown the installation as it would be applied to one-half of a pair of boilers set in battery, the other boiler being omitted. 1 designates the outside wall of the boiler and 2 the battery or dividing wall between the boiler shown and the adjacent boiler not shown. Opening 4 is provided in boiler wall 1 in which is fixed wall box 3. Through this opening extends the nozzled cleaner element designated generally by the reference character 6 extending adjacent the boiler tubes 8 from which it is supported by the water cooled hangers or bearings 7. The operating head located outside of boiler wall 1 is indicated generally by the reference character 5. In this head the nozzled cleaner element is journaled and from this head it receives the cleaning fluid and the cooling fluid. The head is also provided with suitable operating means for rotating the nozzled cleaner element.

As can best be seen by Figure 3, the nozzled cleaner element comprises essentially, in this

modification, three concentric tubes. The outer tube 10 is fixed as by set screws 58 to an inner tube 11. To this inner tube 11 is supplied a cleaning fluid, preferably a liquid such as water, in a manner to be hereinafter described. From this tube 11 the cleaning fluid is discharged through opening 16 in the outer tube 10. Welded at 13 to tube 11 is the nozzle supply tube 12, which, in turn, is welded or brazed to tube 10 through the pad 15 to which it is welded as at 14. 10 It is an essential feature of this nozzle construction that flexibility is provided to take account of differential expansion between the outer tube 10 and the inner tube 11 due to probable differences in temperature to which these tubes may 15 be subjected. It has been, heretofore, observed to be a fault of water jacketed elements of conventional construction in which the nozzle in the outer tube is supplied directly by a short tube leading from the inner tube that differential expansion causes leakage in the nozzle, either at the outer or the inner tube, thus permitting escape of the cooling liquid or fluid which passes through the jacket or space between the inner and outer tubes. It will be readily evident that 20 the construction of the tube 12 is such as to afford ample flexibility thus taking account of any strain which might be developed between the tube 12 and its connection to tube 11 or tube 10 due to possible differential expansion between 25 these tubes 10 and 11. This particular nozzle construction is an essential feature of the instant invention.

Cleaning fluid admitted to the interior of tube 11 is discharged through opening 16 adjacent 35 the portions of the boiler heating surface to be cleaned, such as the tubes 8.

The construction of the nozzled cleaner element is completed by the innermost concentric tube 17 which forms a part of the cooling fluid 40 circulation system to be hereinafter described. As indicated in Figure 1 the outer tube 10 is closed by a suitable welded plug 65. At the end of the middle tube 11 is provided the plug 66 through which passes the cooling fluid circulating tube 17 opening into space 18 formed at the end of outer tube 10. In the form shown the inner circulating tube 17 is stationary, while the outer tube 10 and the cleaning fluid conducting tube 11 are fixed together and rotate together 45 as a unit. Any suitable construction may be provided in the closure 66 of the tube 11, such as a packing gland or the like, not shown, to prevent leakage of the cooling fluid or liquid, such as water, into the cleaning fluid supply pipe 11. It 50 55

is obvious that this innermost cooling fluid circulating pipe 17 could be fixed and rotatable with the other pipes 10 and 11, depending upon the type of joint made in the stationary operating head outside the boiler wall.

The construction of the stationary operating head 5, located outside the boiler wall, can best be seen by reference to Figure 5. This comprises essentially the stationary fitting 18 to which is joined the stationary cleaning fluid supply elbow 25 as by threaded collar 26 in conjunction with threaded collar 64.

Fixed to the outboard end of the outer tube 10 is nipple 19 which makes a rotatable fluid tight joint in the stationary fitting 18 by means of the special gasket member 20 and the threaded collar member 21. Fixed to the end of tube 11 is the member 22 which is held in position against a shoulder on elbow 25 by means of the collars 26 and 64. Special gasket members 23 and 24 are provided to make a fluid tight rotatable joint at this point. The collars 26 and 21 are threadably adjustable on the stationary fitting 18 to vary the pressure applied to the special gasket members to insure free rotatability of the tubular members in the stationary fitting 18, while, at the same time, compressing the gasket member sufficiently to insure a fluid tight joint. The innermost pipe 17 extends outwardly through the elbow 25, which elbow is provided with a boss 28 receiving the packing gland 29. The end of tube 17 is fitted with the elbow 30 having the threaded opening 31.

Circulation of the cooling fluid and the course of the cleaning fluid can readily be seen by reference to Figure 5. Threaded opening 32 is provided on the stationary member 18 to which opening is connected the supply line 35. Cooling fluid is conveniently water from any convenient source. This flows in the direction of the arrow A in Figure 5, through the space between tubes 10 and 11 to the space 18 formed in the end of the outer tube 10. Here it is returned through the tube 17 in the direction of the arrow B from which it is discharged through opening 31 to any suitable point of disposal through the line 33. The cleaning fluid, which may be water, steam, air or the like, is supplied through line 34 fitting in opening 27 and passes through the space between tubes 11 and 17 in the direction of the arrow C in Figure 5. As pointed out above, the connection of tube 17 to the stationary head could be readily modified as by changing the type of joint 29 so that this inner tube 17 could be fixed to and rotatable with tubes 10 and 11. This is no essential feature of the present invention and is not further shown.

It is an important feature of the present invention that the bearings or supports for the nozzleled cleaner tube 6 are formed of tubular members through which a cooling fluid or liquid, such as water, is circulated. These bearings consist, essentially, of a number of U-bends 7 to which water is supplied from the line 47 extending through opening 48 to the outside of the boiler. These tubular members constituting the bearings and the supply pipes therefor may be made up in any convenient sections, connected by couplings as at 49. At 50 is designated the outlet from the bearing circulating system which may be conveniently led to the front of the boiler through an opening 51 formed in the battery wall 2. It is obvious that the method of leading the cooling fluid or liquid to the bearings and

the method of taking the cooling liquid therefrom may be varied to suit conditions.

It will thus be seen that applicant has provided means to cool the nozzleled cleaner element and to support the cooled nozzleled cleaner element on bearing or hanger members which are also fluid cooled. This makes possible the location of the element and bearing in locations or in zones thought heretofore impossible. This can readily be seen by a glance at Figure 2. Here the cleaner unit is shown located beneath the lowermost tube of the boiler and at a considerable distance from the boiler header 38. It should be here pointed out that it is usual practice in locating a unit below the lowermost tube of the boiler to locate this closely adjacent the uptake header 38 and provide a special protecting tile underneath the unit. The cooling influence of the header 38 which, of course, is filled with water appreciably prolongs the life of an element located adjacent or close to the header in the standard position. In the case of inventor's unit, however, this can be located at a considerable distance from the header, as shown in Figure 2, there being no necessary disturbance of the front arch 36 or the special protecting tile 37 ordinarily applied to protect the bottom of header 38.

In Figure 4 is shown diagrammatically the piping connections to and from the bearings, to and from the jacket surrounding the nozzleled cleaner element and also the source of cleaning fluid to the element itself. The cooling fluid applied to the bearings through line 47 may be preferably cold water from any suitable source. In like manner, the cooling fluid applied to the jacket through line 35 may also be cold water taken from any suitable source. As before pointed out, the cleaning fluid used in nozzleled element 11 may be steam, air or water. In case water is used, this may be conveniently taken from the boiler feed or blow-down line 52, this water being led through valve 53 and associated lines to equalizing chamber 55. In case water from the blow-down line is taken as cleaning fluid, this pressure equalizing chamber 55 may also serve as a settling or sediment chamber, the pipe 54 from the blow-down line being led to a point intermediate the length of the settling chamber. Sediment or the like from the blow-down line may conveniently be removed through line 56 and valve 57 before the water is passed to the nozzleled cleaner element in order to minimize the amount of sediment, scale or the like which passes to the nozzleled cleaner element.

The means for rotating the nozzleled cleaner element assembly will now be described. Bracket 39 is fixed in the boiler wall by any suitable means, such as the bolts 40. Mounted on this bracket are the bearings 41 between which extends shaft 42. Fixed to this shaft is the pinion 43 and sheave wheel 45 with which is associated chain 46. Fixed to the tubular member 10 where it extends outside the boiler wall is the large gear 44 engaging the pinion 43. Rotation of the sheave wheel 45 is thus seen to rotate the outer tubular member 10 and with it, of course, the nozzleled cleaner tube 11. A suitable clamping member 67 surrounds the tube 10, being fixed to collar 68 in which the tube 10 is rotatable. The member 67 is fixed in any suitable manner to bracket 39 to thereby maintain suitable registry or engagement of the pinion 43 and gear 44 at all times.

The application shown particularly in Figure 1 is, as stated, adapted for use in connection with boilers set in battery. It is also applicable in the

- case of wide boilers in which a double installation of units is necessary, one unit coming in from each side and extending substantially to midway of the boiler. In this case, of course, a 5 slightly different arrangement of the return line 50 from the bearings 7 will be necessary, although in general this line could be led to the front of the boiler in the manner described with reference to Figure 1.
- 10 In Figure 6 is shown a somewhat simplified modification applicable in the case of a single set boiler of relatively narrow width. In this case the cooling fluid or liquid for the nozzled cleaner element may be conveniently taken out the opposite side of the boiler, eliminating the necessity of the return circulating tube 17, with its associated connections.

In this case the element comprises only two concentric tubes, the outer tube 10' being fixed 20 as by set screws 58' to the inner or nozzled tube 11'. Tube 12' connects the cleaning fluid tube 11' to opening 16' in the manner hereinbefore described. Connected to tube 10' is the nipple 19' engaging the stationary member 18' and 25 forming a fluid tight rotatable connection therewith, the gasket 20' and collar 21' being provided in the manner hereinbefore described. Fixed to the end of the cleaner tube 11' is the disc 22' which forms a fluid tight rotatable joint with 30 the stationary fitting 18' and the elbow 25' in the manner hereinbefore described. Cleaning fluid to the cleaner tube 11' is admitted through opening 27' in elbow 25', the distal or outboard end of the cleaner element 11' being closed as at 35 69. Outside the opposite boiler wall is located the stationary elbow 59 provided with threaded opening 63 through which the cooling fluid or liquid may be discharged. Threadably fixed to 40 the end of tube 10' is the nipple 60 which rotatably engages the stationary elbow 59 and forms a fluid tight connection therewith. The construction at this end to effect this result is similar to that described for the opposite end of the element, a special gasket member 62 and the collar 45 61 being provided for this purpose.

The invention has been described as a boiler cleaner associated with a boiler to clean the heating surfaces of the boiler. It is obvious that it is just as fully applicable to fluid heater cleaners 50 or apparatuses of other types and where the term "boiler" is used, it is intended to be synonymous with "fluid heater". In like manner, where the term "boiler cleaner" is used, it is intended to be synonymous with "fluid heater cleaner".

55 While applicant has shown in detail two different methods of applying his invention, it is obvious that other possible arrangements might be employed.

The description is illustrative only, therefore, 60 and is not definitive of the limits of the inventive idea. The right is, therefore reserved to make such changes in details of construction and arrangement of parts as will fall within the purview of the attached claims.

65 What I claim is:

1. In a boiler cleaner, a nozzled cleaner element and means to support the element comprising a fluid circulating pipe axially bent to engage said cleaner element at spaced points only 70 throughout its length and a source of fluid supply for said fluid circulating pipe independent of the boiler circulation.

2. In a boiler cleaner, a nozzled cleaner element and a support therefor, said support comprising a tubular member axially bent to embrace

the cleaner element at spaced points throughout the length thereof and means independent of the boiler circulation to supply a fluid under pressure to said tubular member.

3. A support for a boiler cleaner element comprising a tubular member, portions of said tubular member being axially bent to at least partially embrace the cleaner element at spaced points throughout the length thereof, a plurality of connections to said tubular member extending 5 outside the boiler setting, and means to supply a fluid under pressure to one of said connections.

4. A support for a boiler cleaner element comprising a tubular member, portions of said tubular member being axially bent to at least partially 15 embrace the cleaner element at spaced points throughout the length thereof, a plurality of connections to said tubular member extending outside the boiler setting, and means independent of the boiler circulation to supply water 20 under pressure to one of said connections.

5. A support for a boiler cleaner element comprising a fluid cooled tubular member having portions axially bent to at least partially 25 embrace the cleaner element at spaced points throughout the length thereof, and a cooling fluid supply connection for said tubular member extending outside the boiler setting.

6. A fluid cooled support for a boiler cleaner element comprising a plurality of pipes each 30 axially bent to form a U-shaped portion, means connecting said pipes, and a tubular member extending outside the boiler setting and connected to one of said pipes to supply a cooling fluid to all of said pipes to cool the same. 35

7. A support for a movable blower pipe comprising a plurality of elements so constructed as to partially embrace a blower pipe at spaced points throughout the length thereof when the blower pipe is installed in a boiler, and means 40 providing a passage for supplying cooling fluid to all of said elements.

8. A support for a movable blower pipe comprising a plurality of elements so constructed as to partially embrace a blower pipe at spaced 45 points throughout the length thereof when the blower pipe is installed in a boiler, and means extending longitudinally of said blower pipe and above the same providing a passage for supplying a cooling fluid to all of said elements. 50

9. A support for a movable blower element, comprising a fixedly mounted fluid cooled element so constructed as to extend longitudinally of said 55 blower element when the latter is installed in a boiler and having a portion engaging said blower element at a point intermediate the ends thereof.

10. A fixed supporting bearing for a movable blower element, comprising a fluid cooled element so constructed as to extend longitudinally of said blower element and above the same when the blower element is installed in a boiler, said fluid 60 cooled element having a portion partially embracing said blower element at a point intermediate the ends thereof. 65

11. A support for a movable blower element, comprising a fixedly mounted tubular element so constructed as to extend longitudinally of said blower element when the latter is installed in a boiler and having portions engaging said 70 blower element at spaced points throughout the length thereof, and means for supplying cooling fluid to said tubular element.

12. A support for a movable blower element, comprising a tubular element so constructed as 75

to extend longitudinally of said blower element above the same when the blower element is installed in a boiler and having portions extending underneath said blower element at spaced points throughout the length thereof, and means for supplying a cooling fluid to said tubular element.

13. A support for a rotatable blower element comprising a tubular element extending longitudinally of said blower element above and in spaced relation to the same, said tubular element having depending U-shaped portions in which the blower element is journaled, and means for

supplying a cooling fluid to said tubular element.

14. A support for a rotatable blower element comprising a plurality of pipe sections each being axially bent to form a U-shaped loop, tubular elements connecting said pipe sections and supporting the same, the blower element being rotatably journaled in the loops formed by said pipe sections, and means for supplying a cooling fluid to said tubular elements and said pipe sections.
